(57) **CLAIM**

I claim the ornamental design for a faux stone ceiling tile, as shown and described.

DESCRIPTION

FIG. 1 is a bottom perspective view of a faux stone ceiling tile, showing my new design;

FIG. 2 is a bottom plan view thereof;

FIG. 3 is a top plan view thereof;

FIG. 4 is a left-side elevational view thereof, the right-side elevational view being a mirror image thereof; and,

FIG. 5 is a front elevational view thereof, the rear elevational view being a mirror image thereof.

The shading pattern on the bottom and side edges of the design denote a rough acoustic ceiling tile surface.
